UNITED STATES PATENT OFFICE.

PLINY J. HOWARD, OF CLEVELAND, OHIO, ASSIGNOR TO THE NATIONAL MALLEABLE CASTINGS COMPANY, OF CLEVELAND, OHIO.

TRUCK SIDE FRAME.

1,104,672.

Specification of Letters Patent. Patented July 21, 1914.

Application filed April 29, 1913. Serial No. 764,299.

To all whom it may concern:

Be it known that I, PLINY J. HOWARD, a citizen of the United States, residing at Cleveland, Cuyahoga county, Ohio, have invented new and useful Improvements in 5 Truck Side Frames, of which the following is a specification, reference being had to the accompanying drawings, forming part of this specification, in which—

10 Figure 1 is an elevation of my improved side frame; Fig. 2 is a section on lines II—II of Fig. 1; Fig. 3 is a section on lines III—III of Fig. 1; Fig. 4 is a detail of a modified form of one of the bearing blocks; 15 Fig. 5 is a section on lines V—V of Fig. 4; Fig. 6 is an elevation of a modification of my invention; and Fig. 7 is a section on lines VII—VII of Fig. 6.

My invention relates to truck side frames 20 and is specifically directed to providing bearings or guides for the bolster "window" which are detachable and against which the truck bolster is designed to bear. My improved bearings protect the columns at the 25 sides of the bolster window from wear, and while in service they are securely attached to the columns they can be readily removed and replaced when worn.

Referring to the drawings: the numeral 30 2 indicates a truck side frame, preferably of integral construction, having the usual tension member 3, the compression member 4 and the columns 5.

The numeral 6 indicates the bolster opening or window, and 7 is the bolster having column guides 8 which secure the bolster to the side frame and prevent endwise movement of the bolster. The channel 9 is bolted to the tension member 3 at the bottom of 40 the window opening 6 and connects the frame 2 with the corresponding frame at the opposite side of the truck.

Bolster bearing blocks 10 are provided to prevent wear by the bolster upon the 45 columns 5, and are adapted to be secured to the upper portions of the columns 5 by rearwardly-projecting lugs 11 which fit into corresponding apertures 12 in the frame 2 and extend into the recesses 13. The keys 50 14 are adapted to be inserted into the slots 15 in the lug 11, and bear on the rear faces of the columns 5 and on the rear sides of the slots 15. To provide for drawing the blocks 10 tightly back against the columns, 55 the keys 14 are made of wedge shape and have their rear faces inclined to correspond

to the incline of the rear sides of the slots 15. The keys 14 each have a split end and are held in wedging position by the spreading or bending of these split ends, as is 60 shown in Fig. 2.

In Figs. 1, 2 and 3 I have shown the bolster opening of such cross-section that the bolster can be inserted into the lower portion of the window in a horizontal position 65 and then raised without tipping between the blocks 10, in which position it will be held by the column guides 8 which bear against the side face of the blocks 10. The blocks 10 which have flanges 16 extending about 70 the sides of the columns 5, take all of the wear occasioned on the frame by the bolster, and adequately protect the side frames. When it is desired to remove the bearing blocks because of wear, the bolster is dropped 75 down into the lower portion of the window, the keys 14 are withdrawn and the blocks 11 are then free for removal.

In Figs. 4 and 5 I show a modified form of bolster bearing block 10', in which the 80 lug 11' is made separate in the form of a headed bolt. The head 17 of the bolt or lug 11' fits in a recess 18 in the bearing face of the block. The slots in the bolts 11' preferably have their rear faces inclined 85 corresponding to the incline of the wedge keys so that as keys are driven in they will draw back the bolts tight in the recesses 18 of the blocks and will thus hold the blocks securely against the columns. 90

In the modification shown in Figs. 6 and 7, the blocks 10² are secured in recesses 19 in the upper portion of the columns, and the lower faces of the blocks are supported on shoulders 20 formed in the columns by the 95 lower edges of the recesses 19. The blocks 10² are secured to the columns by the lug 11² and keys 14² in the manner described above. In this modification the bolster window is of such size that the bolster may be 100 inserted through the recessed upper portion of the window and dropped into the lower portion of the window. After putting in place the blocks 11² the bolster may then be raised to its normal position between 105 the blocks 10².

It is obvious that various changes may be made in the constructions which I have shown and described herein without departing from my invention.

What I claim is:

1. In a truck side frame having an open-

ing therein for a bolster, bearing blocks for the bolster in the upper part of said opening, means for attaching the bearing blocks to the side frame comprising a wedge ⁵ operating with a pin carried on each block and with a portion of the side frame, the said wedge being adapted to be inserted into registering apertures in the side frame and pin and to draw the bearing block ¹⁰ tightly against the face of the bolster opening.

2. In a truck side frame having an opening therein for the bolster, bearing blocks for the bolster in the upper part of said ¹⁵ opening, each of said bearing blocks having a rearwardly extending dowel shaped projection, registering apertures in the frame and in the projection for the reception of a wedging key, the said wedge being adapted ²⁰ to draw the bearing block tightly against the face of the bolster opening and to hold it in such position.

3. In a truck side frame having therein an opening for the bolster, apertured ⁵ columns at the side of the opening, a bearing block for the bolster in the upper part of said opening having a slotted rearward ex-

tension coöperating with an aperture in a column, a recess in the frame communicating with said aperture and a wedge shaped ³⁰ key for insertion through said recess into the slot in the extension, the said wedge shaped key being adapted to draw the block against said column and to hold it in such ³⁵ position.

4. In a truck side frame having therein an opening for the bolster, columns at the sides of the opening, each column having an offset upper portion, bearing blocks for the bolster adapted to fit in each of said offset ⁴⁰ portions and to be held by the offset against vertical movement, each of said bearing blocks having a slotted rearward extension coöperating with an opening in a column, an aperture in the side frame, and a wedge ⁴⁵ shaped key adapted for insertion through said aperture and said slot in the extension for drawing a bearing block back against a column and for securing it to the side frame.

PLINY J. HOWARD.
